UNITED STATES PATENT OFFICE.

JOSIAH D. WHITNEY, OF BRATTLEBOROUGH, VERMONT.

MANUFACTURE OF REEDS FOR MUSICAL INSTRUMENTS.

SPECIFICATION forming part of Letters Patent No. 338,007, dated March 16, 1886.

Application filed June 25, 1885. Serial No. 169,702. (No specimens.)

To all whom it may concern:

Be it known that I, JOSIAH D. WHITNEY, of Brattleborough, in the county of Windham and State of Vermont, have invented new Improvements in Manufacture of Reeds for Musical Instruments; and I do hereby declare the following, when taken in connection with accompanying drawings and the letters of reference marked thereon, to be a full, clear, and exact description of the same, and which said drawings constitute part of this specification, and represent, in—

Figure 1, a perspective view of a reed, looking upon the face side; Fig. 2, a longitudinal section through the heel portion of the reed, illustrating the first operation in the formation of the rivets; Fig. 3, the same section after the second operation, the tongue applied, the upsetting or riveting indicated in broken lines.

The object of my invention is to avoid the possibility of the detachment of the reed when once secured to the body; and it consists in first punching the body from the face side, to throw a corresponding projection upon the opposite side, the projection being larger in diameter than the recess punched in the face side, then applying the tongue to the face side over the recesses formed by the punch, and then forcing the metal, which thus forms the stud, through the smaller recesses, thence through the tongue, and riveting them down, and whereby the portion of the stud within the body is of larger diameter than the projecting stud itself, as more fully hereinafter described. I first take the usual body, B, (see Fig. 2,) and upon its face side—that is, the side to which the tongue is to be applied—and at the usual position for riveting, I apply a punch in size corresponding to the stud to be produced and to the perforation through the tongue, and under pressure form the recesses *d* upon that face side, forcing the metal through the body to form corresponding projections, *e*, upon the reverse side, but of larger diameter than the recesses upon the face side. The best instruments for forming this recess on the face side and projection on the opposite side is a punch and a die, the die having openings in it corresponding to the larger diameter required for the projections on the reverse side, and the punch, as before stated, of a diameter corresponding to the recesses in the face side, the

body of the reed laid upon the die face side up and in the proper relative position to the openings in the die, and so that the punches when forced toward the die will produce the recesses on the face side, and the larger diameter projections *e* on the opposite side. This operation substantially separates the stud portion from the body, as indicated in Fig. 2. Then, as the next operation I apply the tongue *a* upon the faceside, as indicated in broken lines, Fig. 2, the heel end over the recesses in the face of the body of the reed, and with its tongue in the proper relation to the slot in the reed; then return the stud portion, formed as before mentioned, and drive it through the heel portion of the tongue, to form the rivets to secure the tongue to the reed. This operation is best performed by means of a punch applied to the projecting portions *e* on the reverse side, the punch being substantially the diameter of the projecting portions *e*. The tongue resting upon a die having openings corresponding to the recesses *d*, the metal or stud portions *f* are forced toward the face and through the tongue, as indicated in Fig. 3, the hole through the tongue, and the stud projecting being smaller than the reverse or head end of the stud, as seen in Fig. 3. Then the studs are riveted down upon the tongue in the usual manner, as indicated in broken lines, Fig. 3. By this construction the tongues are secured as if by a conical rivet introduced through a hole in the body from the reverse side, the hole itself gradually contracting toward the face side, and the stud of corresponding frustum-of-cone shape, so that the stud takes a firm bearing in the body to resist the strain or tendency of the tongue to draw the stud through, and detachment of the tongue without first removing the upset or riveted portion of the stud is impossible.

The driving of the studs into the contracted hole in the body makes the firmest possible connection between the stud and the body to hold the rivet in place.

I do not wish to be understood as claiming, broadly, the attachment of tongues to reeds by means of rivets forced from the metal of the body of the reed through the tongue, as such, I am aware, is not new.

I claim—

The herein-described improvement in the

manufacture of reeds for musical instruments, consisting in first punching the body where the rivets are required from the face side toward the reverse side, forming recesses on the face side and corresponding projections on the reverse side, but the projections on the reverse side of larger diameter than the recesses on the face side, then applying the tongue upon the face side of the body within 5 the heel end and over said recesses, then forcing the metal of the body displaced in the formation of said recesses and projections in

the reverse direction through the body and through the tongue, to form projecting studs on the body through the tongue, the said projecting studs from the face being of smaller diameter than upon the reverse side, the said projecting studs riveted upon the tongues, substantially as described. 15

JOSIAH D. WHITNEY.
